UNDERWATER GOGGLE

Robert Malcom, Chicago, Ill., assignor to Chicago Eye Shield Company, a corporation of Illinois

Application June 30, 1941, Serial No. 400,472

3 Claims.

(Cl. 2—14)

This invention relates to a goggle or shield to be worn as facial protection under water.

It is an object of the invention to provide an article of this kind that is capable of substantially water-tight fit with the face of the user, and covers, protects, and prevents access of water to his eyes and nose, and that has a transparent pane in front through which he can see.

Further, it is an object of the invention to provide an article of those characteristics that also gives substantially water-tight coverage and protection to the ears of the user.

Another object of the invention is to provide such an article, comprising a glass carrying frame or body and ear covers, formed integrally as a single structure of pliable material that easily conforms itself to substantially water-tight fit with the parts of the head to which it is held while in use.

When considered with the description herein, characteristics of the invention are apparent in the accompanying drawings, forming part hereof, wherein an embodiment is disclosed for purpose of explanation.

Like reference-characters refer to corresponding parts in the views of the drawings, of which—

Fig. 1 is a side view, a part being in section;

Fig. 2 is a top view, partly in section;

Fig. 3 is a bottom view;

Fig. 4 is a rear view;

Fig. 5 is a section on line 5—5, Fig. 1;

Fig. 6 is a section illustrative of a modification in the facepiece.

The goggle comprises a facepiece of pliable and elastic self-form-sustaining material impervious to water, such as soft rubber, that is moldable to shape.

The body of the facepiece is a comparatively thick wall 7 that encompasses the space in front of the eyes and nose of a user. The wall may be circular or other tubular form. At its front it has an inwardly disposed planar flange 8, next to and inside of which is a groove 9 in the wall. The wall protrudes radially at the groove as an external rib 10 to accommodate the groove without decreasing the wall thickness.

A rather thick transparent pane 11, of plate glass or other suitable material, is disposed at its periphery in the groove, and it is overlapped by the flange 8. It has a water-tight joint with the wall by fitting closely in the groove and against the flange. Such a joint may be had by making the pane of slightly larger diameter than the normal diameter of the groove and by stretching the wall when the pane is being put into place, con-

strictive action of the wall material affording a seal, or the joint may be sealed with cement or other suitable material.

Instead of one pane 11 sealed in place as shown by Figs. 1 and 2, two such panes may be sealed similarly in the facepiece body as shown by Fig. 6.

The rear edge of the body wall 7 is curved to conform generally to and to have tight contact with the average faces against which it is held while in use, the pliability of the material enabling it to adjust itself to facial irregularities.

For this purpose, the edge at the top is curved, as designated at 12, to conform to the brow or forehead over the eyes; thence it curves backwardly on each side, as designated at 13, to tips 14 that contact with sides of the face at the sides of the eyes and nose; and thence it curves downwardly and forwardly for contact with the cheeks, as shown at 15, and thence forwardly from each side for contact with the upper lip, as shown at 16.

With this conformation of the rear edge of the body wall, when the edge is drawn and held against the face by a headband 17, the goggle covers the eyes and nose of the user, there is substantially water-tight seal with the face, and the user is able to see under water through the pane at the front.

The headband, which is provided with a buckle 18 or other suitable adjustable fastener for its free ends, may be attached to the body in any suitable manner. As shown, slotted protuberances 19 are molded integrally on opposite sides of the body at or near the front thereof, and front ends of the headband are disposed therethrough. Each of these headband ends has an enlargement 20, which bears against a slotted plate 21 so that the band is prevented from pulling out of the protuberances.

It is advantageous to position the protuberances at the front of the shield body, because this enables the backward stress imposed thereon by the headband to be distributed throughout the pliable wall to its facial edge and thus contribute to adjustment of the edge to the face.

An ear flap 22 extends backwardly from each side of the body of the goggle. They are formed integrally with and of the same material as the body. The flaps are thinner than the body wall, they are long enough to extend to the back of the head, and wide enough and so disposed to cover the ears. They are continuations of the body wall, and where they go off from that thicker wall they leave an end surface on the latter for sealing contact with the face, as shown at 23 in Fig. 2.

The headband overlaps the ear flaps and holds them against and causes them to protect the ears of the user when the goggle is in place on his head. The flaps afford a layer of wide soft material between the headband and the ears and other parts of the head, and thus the tension of the headband over those parts is more comfortable than if the narrower band pressed directly thereagainst.

I claim:

1. A goggle capable of covering the eyes and nose of a user, comprising a body formed of a curved wall of pliable self-form-sustaining material have a rear edge conformable to facial contour with substantially liquid tight seal therewith, a transparent pane at the front of said body, ear flaps extending rearwardly from sides of said body, and a headband connected with said body and overlapping said flaps to hold said body and flaps respectively against the face and ears of a user.

2. A goggle for underwater use comprising a body formed with a comparatively thick tubular

wall of soft pliable rubber capable of encompassing the space in front of the eyes and nose of a user, and having a rear edge conformable to the face with a tight seal therewith, a transparent pane in the front of said body having liquid tight seal with its wall, and a headband attached directly to said body at its front.

3. A goggle capable of covering the eyes and nose of a user comprising as a unitary protective part a body formed with a comparatively thick tubular wall of soft pliable rubber capable of encompassing the space in front of the eyes and nose and having a rear edge conformable to the face with a substantially water tight seal and flaps integrally formed with said body and extending rearwardly from opposite sides thereof and sufficiently wide to cover the ears, a headband attached near the front of said body on the same opposite sides as said flaps, and a transparent pane in the front of said body having substantially water tight seal with its wall.

ROBERT MALCOLM.
